DESIGN FOR A VALVE HANDLE

Jacques Stanitz, Warren, Ohio, assignor to
Mullins Manufacturing Corporation, Salem,
Ohio, a corporation of New York

Application March 2, 1945, Serial No. 118,219

Term of patent 7 years

(Cl. D78—1)

To all whom it may concern:

Be it known that I, Jacques Stanitz, a citizen
of the United States, residing at Warren, in the
county of Trumbull and State of Ohio, have in-
vented a new, original, and ornamental Design
for Valve Handle, of which the following is a
specification, reference being had to the accom-
panying drawing, forming part thereof.

Figure 1 is a top plan view of a valve handle
showing my new design;

Fig. 2 is a side elevation thereof;
Fig. 3 is an end elevation thereof; and
Fig. 4 is a perspective view thereof.

I claim:

The ornamental design for a valve handle, sub-
stantially as shown.

JACQUES STANITZ.
